(57) **CLAIM**

An ornamental design for a shoelace knot cover for wrestling footwear, as shown and described.

DESCRIPTION

FIG. 1 is a left side elevation view showing a preferred embodiment of a shoelace knot cover for wrestling footwear of the present invention located on an environment of a wrestling shoe that is shown in dashed lines, a right side elevation view being a mirror image of the left side elevation view;

FIG. 2 is a front elevation view of the shoelace knot cover for wrestling footwear of FIG. 1; and,

FIG. 3 is a rear elevation view of the shoelace knot cover for wrestling footwear of FIG. 1.

The broken lines of FIG. 1 represent an environment of a wrestling shoe on which the present invention may be deployed and does not form of a part of the present invention.
